UNITED STATES PATENT OFFICE

JOHN H. ANDRESEN, OF GLEN ROCK, NEW JERSEY

TEXTILE PRINTING MACHINE

Application filed December 13, 1930. Serial No. 502,032.

This invention relates to improvements in textile printing machines of the type embodying an impression cylinder to which rotary motion is imparted by frictional contact with a series of printing rollers, and a gum roller rotating in contact with the impression cylinder. The principal object of the invention is to provide an improved machine of this character in which means is provided for transmitting motion from the impression cylinder to the gum roller at a surface speed at least as great as that of the impression cylinder, whereby a single gum roller of a convenient diameter may be used in combination with sets of printing rollers of different diameters without producing slippage.

Other objects and advantages of the invention will appear as the description proceeds.

The drawing accompanying this specification is an end view, partly broken away, of a machine embodying the features of the present invention.

Referring to the drawing, 1 designates the frame of a textile printing machine, in which is mounted for free rotation a cylinder or impression roller 2 of comparatively large diameter, in contact with the surface of which the usual blanket 3 travels during its passage from guide roller 4 to guide roller 5. A plurality of printing rollers 6, and a gum roller 7 are mounted in bearings carried by movable blocks 8, for rotation in frictional contact with the surface of the impression cylinder 2, the contact pressure being controlled by means of suitable screw shafts 9 swiveled in the bearings 8 and threaded through fixed portions of the machine frame in the well-known manner.

Motion is imparted to the printing rollers 6 by means of pinions 10 secured on the shafts of the rollers, said pinions meshing with a gear 11 mounted for rotation on a stud shaft 12, secured in the frame of the machine, motion being imparted to the gear by a pinion 12^a from any suitable source of power.

As is the usual practice in the operation of machines of this type, motion is imparted to the impression cylinder 2 by frictional contact with the printing rollers 6, which, as above stated, receive motion by means of the

gear 11 and pinions 10. It is the generally accepted practice to provide a pinion, similar to the pinions 10, on the shaft of the gum roller 7, said gum-roller pinion being also in mesh with gear 11. However, inasmuch as the gum roller is in frictional contact with the impression cylinder, which latter is driven by frictional contact with the printing rollers, it follows that under such practice the diameter of the gum roller must always be the same as that of the set of printing rollers with which it is to be used, and since the latter vary considerably in diameter, depending on the designs to be printed, a large supply of gum rollers of varying diameters must be kept in stock, which of course is uneconomical from the standpoint of cost as well as the space they occupy when not in use. The present invention is intended to provide a combination of members whereby a single gum roller may be used in conjunction with printing rollers of any diameter, thereby eliminating the necessity of providing a number of gum rollers of different diameters.

In the machine as shown herein, the gum roller 7 is maintained in frictional contact with the impression cylinder, and is not geared to the gear 11. The gum roller, however, does not depend for its motion on this frictional contact, but nevertheless receives its driving motion from the surface of the impression cylinder. For this purpose a shaft 13 is mounted for rotation in movable bearings carried by the machine frame, said shaft carrying a roller 14 in frictional contact with the surface of the impression cylinder. As shown herein the roller 14 engages the impression cylinder at a portion of said cylinder between the "runs" of the blanket 3, this being the preferred point of contact with the surface of the impression cylinder.

However, it would be practical to dispose the roller 14 outside of the blanket so as to engage the cylinder through said blanket, for instance, at a point above the point of entry of the blanket between the cylinder and the first printing roller. Motion is thus transmitted from the impression cylinder to the roller 14 by frictional contact. The shaft 13

carries at one end a sprocket 15, and on the corresponding end of the gum roller 7 is secured a similar sprocket 16, which sprockets are engaged by an endless chain 17, whereby motion is transmitted from roller 14 to the gum roller 7. The shaft bearings of the roller 14 are adjustable toward and from the impression cylinder 2, by means of a swiveled screw 18, in the same manner as the printing rollers and gum roller. The sprocket chain is preferably provided with a tensioning means, shown herein as an idler sprocket 19 over which the chain passes, the shaft of said sprocket being itself mounted in movable bearings controlled by a swiveled adjusting screw 20. It is of course understood that the expression "surface of the impression cylinder" as herein used is intended to mean the usual working surface of the cylinder, which may have a cloth or rubber covering.

From the foregoing it will be seen that while the gum roller 7 receives its rotary motion from the impression cylinder, the transmission of such motion is entirely independent of the contact of the gum roller itself with the impression cylinder. Consequently, there is no necessity for changing the gum roller regardless of the girth of the printing or design rollers because the gum roller is always driven at a surface speed at least equal to that of the impression cylinder, which in turn is determined by surface contact with the printing rollers. As a matter of fact, the ratio of the sprockets 15 and 16 is preferably such as to cause the gum roller to rotate at a surface speed slightly greater than that of the impression cylinder.

I am aware that attempts have been made to eliminate the necessity of carrying in stock a gum roller corresponding in diameter to each set of printing rollers, and that such attempts have contemplated doing away with the pinion for driving the gum roller and causing the latter to be driven by frictional contact with the impression cylinder through the intermediary of the blanket and the fabric being printed. However, such a construction is obviously impractical, for the reason that here is considerable slippage of the gum roller with relation to the impression cylinder and consequently considerable "puckering" or piling up of the goods at the point of entry between the impression cylinder and the gum roller.

It is believed that the operation of the machine will be understood from the foregoing description, taken in connection with the drawing. The fabric or goods to be printed is fed into the machine over a roller 21 and passes along with the blanket 3 between the successive printing rollers and the impression cylinder and between the impression cylinder and the gum roller, whence it is led out over a roller 22, in the usual manner, motion being imparted to the printing

rollers by the shaft 12 through the pinion and gear connection hereinbefore described. The printing rollers, by their frictional contact, through the fabric and blanket, with the impression cylinder, transmit motion to said cylinder, which in turn transmits motion to the roller 14 which is in direct contact therewith, and which roller, through the sprocket and chain connection, positively drives the gum roller 7. It will, of course, be understood that the machine may be provided with as many printing rollers as may be desirable or necessary, and that other details of construction may be modified without departing from the spirit and scope of the invention as set forth in the appended claims.

Having thus described my invention, what I claim is:

1. In a textile printing machine, the combination of a printing roller, means for imparting rotary motion to said roller, an impression cylinder in frictional contact with said printing roller and adapted to be driven thereby, a gum roller mounted for rotation in contact with said impression cylinder, and means driven by the impression cylinder for imparting motion to said gum roller and adapted to maintain a predetermined ratio between the surface speed of the impression cylinder and that of the gum roller.

2. In a textile printing machine, the combination of a printing roller, means for imparting rotary motion to said roller, an impression cylinder in frictional contact with said printing roller and adapted to be driven thereby, a gum roller mounted for rotation in contact with said impression cylinder, a rotatable member in frictional contact with the impression cylinder for receiving motion therefrom at a point distant from said gum roller, and means for transmitting motion from said member to said gum roller at a surface speed at least as great as that of the impression cylinder.

3. In a textile printing machine, the combination of an impression cylinder, a fabric web in engagement with a portion of the surface of said cylinder, a plurality of printing rollers in frictional engagement with said web and impression cylinder, means for imparting rotary motion to said printing rollers thereby to cause rotation of the impression cylinder, a gum roller in contact with said web and impression cylinder, a roller in direct frictional contact with the impression cylinder at a portion thereof between the runs of said web, and means for transmitting motion from said direct-contact roller to said gum roller at a surface speed at least as great as that of the impression cylinder.

In testimony whereof I have signed my name to this specification.

JOHN H. ANDRESEN. 130
